UNITED STATES PATENT OFFICE.

LOUIS N. MOSIER, OF HARLEM, MISSOURI.

DETECTOR-BAR.

SPECIFICATION forming part of Letters Patent No. 447,694, dated March 3, 1891.

Application filed March 27, 1890. Renewed January 22, 1891. Serial No. 378,678. (No model.)

To all whom it may concern:

Be it known that I, LOUIS N. MOSIER, a citizen of the United States of America, residing at Harlem, in the county of Clay and State of Missouri, have invented certain new and useful Improvements in Detector-Bars; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My improvements relate to detector-bars which are employed to detect the presence of a car or cars upon a railway-track and operate switches.

The object of the invention is to provide means whereby a detector-bar can be readily attached to a rail of ordinary construction, so that all the parts thereof will be located above the ties or lower edge of the rail, and which can be attached to the rail without displacing the same; and it consists in providing a block which is adapted to be rigidly secured to the web of the rail by means of a bolt, said block also carrying a bolt to which one end of links or arms is pivoted, while the opposite ends are pivotally secured to the bar, the parts being organized so that when the detector-bar is lowered it will rest upon the heads of the bolts which secure the blocks to the rails, and when elevated will be inclined, so that the upper edge of the detector-bar will be over the tread of the rail, so as to be positively acted upon by the car-wheels.

In the accompanying drawings, Figure 1 is a longitudinal elevation or side view, the detector-bar being shown lowered in full lines and elevated in dotted lines. Figs. 2 and 3 are vertical sectional views taken through the lines $x\ x$ and $y\ y$, respectively, of Fig. 1. Fig. 4 is a detail perspective view of the supporting-block detached.

A refers to the railroad-rail, which is of ordinary construction and is provided at suitable points with perforations or openings a , through which pass bolts B for securing the blocks C in place. The bolt B is screw-threaded at one end, while the opposite end has a rectangular head formed thereon, the sides of which project from the body of the bolt, and

the lower end depends, leaving the upper edge of said head substantially on a line with the shank. This is a desired construction, as upon the upper edge of the head of the bolt the detector-bar will rest when down.

The block C has on its outer surface or inclined edge a recess b , within which a portion of the head of the bolt B will lie, this recess not only preventing the rotation of the head of the bolt, but also forming a bearing for the same. This block is provided at its ends with projections which conform to the shape of the rail and provides a space in which the head of the bolt D may lie, as well as lightening the block.

The bolt D is provided adjacent to the outer inclined surface of the block C with a washer or ring d , and next to this ring lie the arms or links E, said links moving freely upon the bolt D, and are secured thereto by a washer and pin. To the outer ends of the links E is secured the detector-bar F by bolts d' , which pass through the links and are secured thereto by a pin or nut.

The detector-bar has attached thereto at a suitable point an outwardly-projecting pin G, to which the connecting-rod is attached, which leads to levers or other devices for operating the switch or other mechanism for locking the switch when the cars are upon the track, or for other purposes for which detector-bars are usually employed.

The detector-bar when depressed may not only rest upon the bolts D, but, if desired, can also have a bearing upon the washers d , and it will be observed that by the construction and arrangement of the parts herein shown the outer edges of the blocks are at an inclination with the web of the rail, as well as the operating parts, so that when the detector-bar is raised it will be moved over the tread of the rail to be positively acted upon by the car-wheels.

I am aware that prior to my invention a detector-bar has been pivoted to links or arms, so that it will be moved when raised at an inclination with the rail, and I do not claim such construction, broadly; but

What I claim as new, and desire to secure by Letters Patent, is—

1. The combination, with a railroad-rail, of recessed blocks secured to the web of the

rail by bolts B, said blocks having outwardly and upwardly inclined bolts D, upon which are pivoted links or arms E, and a detector-bar secured to the upper ends of said arms, the 5 bolts B serving the two fold purpose of holding the blocks C to the rails and as stops for the detector-bar, substantially as set forth.

2. In combination with a railroad-rail, blocks C, having their ends shaped to con-10 form to the rail, bolts B for securing said blocks in place, upwardly-inclined bolts D, secured to the blocks, links loosely pivoted thereon, and a detector-bar having upwardly-inclined projections or bolts d' for attaching 15 the upper ends of the links thereto, substantially as set forth.

3. The combination, with a railroad-rail, of blocks C, having inclined recesses b, horizon-

tal bolts B for securing said blocks to the rail, said bolts having rectangular heads 20 adapted to partially lie within the recesses b, bolts or pintles L secured to the blocks C at an upward inclination, washers d, and links E, pivotally mounted on the bolts D and pivotally connected to the detector-bar, so that when 25 the detector-bar is elevated the upper edge thereof will be over the edge of the rail and when lowered will rest upon the projecting heads of the bolts B, substantially as shown, and for the purpose set forth.

In testimony whereof I affix my signature in presence of two witnesses.

LOUIS N. MOSIER.
